UNITED STATES PATENT OFFICE.

FELIKS SEBESTAKOWICZ, OF MCKEESPORT, PENNSYLVANIA.

RAIL JOINT.

1,411,525.

Specification of Letters Patent. Patented Apr. 4, 1922.

Application filed October 29, 1921. Serial No. 511,258.

To all whom it may concern:

Be it known that I, FELIKS SEBESTAKOWICZ, a citizen of Poland, residing at McKeesport, in the county of Allegheny and State of Pennsylvania, have invented certain new and useful Improvements in Rail Joints, of which the following is a specification.

This invention relates to certain new and useful improvements in rail joints and principally has reference to the provision of means for the joining of rails end to end in an efficient manner without the necessity of employing threaded bolts and nuts which have been found objectionable for various well known reasons.

The primary object of the invention is to provide a rail joint with opposite fish plates interlocking with the rail ends to hold them against separation, and means associated with the fish plates for holding the latter against separation and into tight interlocking engagement with the rail ends.

Still another object of the invention is to provide a rail joint of the above kind including a rail supporting plate with a longitudinal cam carrying shaft rotatable for releasing or clamping the fish plates at will.

Still another object of the invention is to generally simplify and improve rail joints.

With the above general objects in view and others that will appear as the nature of the invention is better understood, the invention consists in the novel form, combination and arrangement of parts hereinafter more fully described in connection with the accompanying drawing and in which like characters of reference indicate corresponding parts throughout the several views.

40 In the drawing,

Figure 1 is a fragmentary side elevational view of a rail joint constructed in accordance with the present invention,

Figure 2 is a top plan view thereof with the cams in clamping position,

Figure 3 is a horizontal sectional view taken upon line III—III of Figure 1 with the clamping cams released,

Figure 4 is a vertical sectional view taken upon line IV—IV of Figure 1,

Figure 5 is a fragmentary top plan view showing one end of the rail supporting plate with the cam shaft removed, and

Figure 6 is a transverse sectional view taken upon line VI—VI of Figure 5.

Referring more in detail to the several

views, the present invention contemplates the provision of simplified means for efficiently connecting the ends of two rail sections 5 and 6 in end to end abutting relation and involves a pair of fish plates 7 flatly engaging the opposite sides of the webs of the rail sections 5 and 6 as well as resting upon the base flanges of said rail sections as shown clearly in Figure 4, the web of each rail section being provided with a plurality of transverse openings for snug reception of lateral pins 8 which are rigid with and preferably integral with the fish plates 7. In this way, the rail sections 5 and 6 are interlocked against separating as long as the fish plates 7 are held tightly clamped against the opposite faces of the webs of the rail sections.

In order to so clamp the fish plates in position, I provide a base or rail supporting plate 9 upon which the rail ends are flatly seated and from one side of which a plurality of lugs 10 project, said lugs having inwardly directed upper ends disposed to 75 abut the adjacent edge of the adjacent fish plate 7. A plurality of lugs 11 project upwardly from the opposite edge of the rail supporting plate 9 and these lugs have inwardly directed upper ends terminating in 80 spaced relation to the adjacent edge of the other or adjacent fish plate 7. The last named lugs have their inwardly directed ends bifurcated or otherwise formed as at 12 to provide longitudinally aligned bearings 90 in which a longitudinal cam shaft 13 is removably journaled for rotation upon a horizontal axis. At spaced points and at opposite sides of the point where the ends of the rails meet, the shaft 13 is provided with cam-shaped enlargements 14 so constructed as to be disengaged from the adjacent fish plate when in one position as shown in Figure 3 whereby the rail supporting plate and the shaft 13 may be slid longitudinally out of 100 the way of the fish plate 7 so as to permit the latter to be disengaged from the rail sections whenever desired, said cam members 14 being further constructed to engage the edge of the adjacent fish plate and co-operate with the lugs 10 for forcing the fish plates together when disposed in another position as shown in Figure 2. The adjacent edge of the fish plate which is engaged by the cams 14 is provided with suitable 110 sockets 15 in which the cams 14 are adapted to seat when in clamping position and in

this way, the parts are held against relative displacement in a direction longitudinally of the rails. One end of the shaft 13 may be squared as at 16 for the reception of a wrench whereby the same may be readily manipulated.

In operation, the rail sections 5 and 6 are disposed in end to end abutting relation as shown in Figure 1 whereupon the fish plates 7 are disposed upon opposite sides of said rail ends with the pins 8 of each fish plate extending through aligned openings in the web of each rail section and the other fish plate. The rail supporting plate 9 is then disposed under the bases of the rail sections 5 and 6 so that the lugs 10 engage the edge of one fish plate and with the cams 14 disengaged from the edge of the other fish plate as shown in Figure 3. The shaft 13 is then turned a portion of a revolution until the cams tightly wedge the fish plates together and enter the sockets 15. The rails will then be effectively held together, and it is obvious that any suitable means may be provided for preventing accidental rotation of shaft 13. The present joint may be advantageously employed between adjacent ties, not shown.

From the foregoing description, it is believed that the construction and operation of the present invention will be readily understood and appreciated by those skilled in the art.

Minor changes may be made without departing from the spirit and scope of the invention as hereinafter claimed.

What is claimed as new is:

1. A rail joint comprising a pair of rail sections having transverse openings through the webs thereof, fish plates disposed upon opposite faces of the rail section webs and having inwardly directed pins extending through the webs of said rail sections, a base plate upon which said rails are seated having upwardly and inwardly directed lugs at one edge thereof engaging the adjacent edge of one of the fish plates, upwardly extending lugs upon the opposite side of said base

plate, and a shaft journaled in the last named lugs having cams arranged to engage the edge of the other fish plate and cooperate with the first named lugs for tightly clamping the fish plates against said rail sections.

2. A rail joint comprising a pair of rail sections having transverse openings through the webs thereof, fish plates disposed upon opposite faces of the rail section webs and having inwardly directed pins extending through the webs of said rail sections, a base plate upon which said rails are seated having upwardly and inwardly directed lugs at one edge thereof engaging the adjacent edge of one of the fish plates, upwardly extending lugs upon the opposite side of said base plate, and a shaft journaled in the last named lugs having cams arranged to engage the edge of the other fish plate and cooperate with the first named lugs for tightly clamping the fish plates against said rail sections, said cam shaft being removably journaled in the upper ends of the second named lugs.

3. A rail joint comprising a pair of rail sections having transverse openings through the webs thereof, fish plates disposed upon opposite faces of the rail section webs and having inwardly directed pins extending through the webs of said rail sections, a base plate upon which said rails are seated having upwardly and inwardly directed lugs at one edge thereof engaging the adjacent edge of one of the fish plates, upwardly extending lugs upon the opposite side of said base plate, and a shaft journaled in the last named lugs having cams arranged to engage the edge of the other fish plate and cooperate with the first named lugs for tightly clamping the fish plates against said rail sections, the fish plate engaged by said cams being provided with sockets for reception of the latter whereby relative longitudinal displacement of the rail supporting plate and the fish plates is prevented.

In testimony whereof I affix my signature. 95
FELIKS SEBESTAKOWICZ.
